UNITED STATES PATENT OFFICE.

CARL C. THOMAS, OF BALTIMORE, MARYLAND.

INTERNAL-COMBUSTION-ENGINE PUMP.

1,343,693.

Specification of Letters Patent. Patented June 15, 1920.

Application filed April 2, 1915, Serial No. 18,817. Renewed April 30, 1920. Serial No. 378,018.

To all whom it may concern:

Be it known that I, CARL C. THOMAS, a citizen of the United States, residing at Baltimore, in the State of Maryland, have invented certain new and useful Improvements in Internal-Combustion-Engine Pumps, of which the following is a specification.

My invention relates to an internal combustion engine pump and to processes of converting heat energy into work and of pumping liquids, fluids, &c.

It is a primary object of the present invention to utilize the highly compressed gases of an internal combustion engine immediately after ignition, or early in the working stroke of said engine, for pumping water or other liquids or fluids, by discharging part of such gases into or against a column of liquid or fluid in a pump conduit while cutting off such discharge before the end of the working stroke and permitting the remaining gases to do work in said engine for operating the same. It is another object of the invention to utilize such compressed gases in an air-lift or gas-lift pump, whereby the liquid or fluid will be elevated and heated by such gases. It is a further object of the invention to utilize the heat energy of the internal combustion engine for pumping and heating liquids, whereby a high efficiency in the operation of said engine is obtained. Further objects of the invention will more clearly appear from the following detail description.

The internal combustion engine used in the pump of the present invention may be of any suitable or preferred construction such as a two or four-cycle engine provided with the usual inlet and outlet connections and valves. Such engines may operate upon any suitable combustible charge such as a mixture of compressed air and combustible fluid, among which fluids, alcohol, gasoline, kerosene and other oils &c. may be mentioned. Such engine I provide with a supplemental or auxiliary outlet together with suitable valve means for discharging therethrough into a pump conduit part of the working gases immediately after ignition or early in the working stroke of said engine. The pump conduit may also vary considerably in its construction and arrangement. In the preferred embodiments of the invention illustrated and described in the present ap-

plication the pump conduit is arranged to be operated upon the air-lift or gas-lift principle, the discharge from said engine being introduced into the pump conduit near the lower level of the water column therein or at 60 a suitable place below the water level therein for elevating or pumping such water or other liquid or fluid.

I will now proceed to describe my invention more in detail, and with particular reference to the accompanying drawings illustrative of certain embodiments thereof, but it is intended and understood that the invention is illustrated by but is not limited to the specific embodiments thereof so illustrated and described except as defined in the appended claims. I will describe my invention as applied to the pumping of water but it will be understood that the invention is also applicable for the pumping of other 75 liquids or fluids or in some cases even solids suitably carried by or suspended in liquids or fluids.

In the accompanying drawings,

Fig. 1 is a perspective view of an internal combustion engine pump embodying the invention.

Fig. 2 is a central vertical section showing the specific construction of the cylinder and pump connections of Fig. 1.

Fig. 3 is an indicator diagram illustrative of the operation of the internal combustion engine pump of the present invention.

Fig. 4 is a central vertical section of a modified construction somewhat similar to that of Fig. 1.

Fig. 5 is a partial end elevation, with parts broken away, of the structure of Fig. 4.

Fig. 6 is a view taken on the line 6—6 of Fig. 4.

Fig. 7 illustrates somewhat diagrammatically a modified form of the invention.

Fig. 8 is a detail view showing a modification of the structure of Fig. 7.

Fig. 9 illustrates a further modification of the invention.

Fig. 10 illustrates still a further modification of the injector nozzle.

Fig. 11 shows a further modified form 105 of the invention, and

Fig. 12 illustrates diagrammatically a still further modification.

Referring first to the embodiments of the invention illustrated in Figs. 1 and 2, the 110

cylinder 1 of a suitable internal combustion engine has a piston 2 of suitable construction connected to a fly wheel 3, the engine as a whole being mounted upon a suitable base 5. The cylinder and engine construction can be varied within rather wide limits as can also the support and arrangement of the engine with respect to the water or other liquid or fluid to be pumped. The engine is not primarily intended for doing external work other than in pumping the liquid and in performing its own engine functions, but the engine can be used for doing such work when desired and in some cases it may be used only for doing such work. Where no external work is desired the fly wheel and connecting rod can be made of lighter construction since the primary function of the engine is to act as an ignition cylinder, or a compression and ignition cylinder, for the explosive charge utilized in the pumping operation while only enough power need be utilized in the engine cylinder to make it perform its engine functions. The engine illustrated has its inlet and outlet connections and valves arranged at the side so that the head of the cylinder is left free. In place of the usual cylinder head, a head 5 is shown applied to the cylinder 1, said head being provided with an integral extension 6 and with an opening leading from the cylinder to said extension, said extension terminating in a head 7 suitably attached thereto.

Arranged in the connection from said cylinder to the extension is the valve seat 8 against which a suitable spring-pressed valve 9 seats, said valve being carried or supported by a stem 10 and being spring-pressed against its seat by a spring 11, the tension of which can be varied by means of sleeve 13 acting upon a plate 15 at the end of the spring. The sleeve 13 acts in a screw-threaded bushing 13^a and can be locked in adjusted position by the nut 14. Surrounding the valve stem and the spring is a protecting flange or cylinder 12 which protects the parts of the valve from injury. The valve illustrated and described may be taken as a type of suitable spring-pressed valve of suitable construction, and it will be understood that the construction of this valve can be varied and valves of different construction and similar operation substituted. The tension of the spring which holds the valve to its seat can be adjusted in accordance with the desired operation of the pump. Thus in a four-cycle engine the valve should remain closed during the compression and exhaust strokes and should open only during the working stroke when the pressure within the cylinder is sufficient to overcome the spring tension. Since the maximum pressure within the cylinder is immediately after ignition or early in the working stroke of the engine

it will be clear that the spring-pressed valve will open at such time and will remain open until part of the working gases have escaped and the pressure has been reduced to permit the valve to close. When the valve closes 70 the remaining gases will continue to do work in the cylinder and cause it to perform its engine functions. Thus in a four-cycle engine the engine should complete its working, exhaust, suction and compression strokes before the next working stroke and discharge of the working gases. The outlet from the extension 6 is upwardly into a water casing 16, provided with a lateral inlet 17 leading from a water supply pipe 18, suitable check 75 valves 19 and 20 being provided in the conduits 16 and 18 to prevent reverse flow of the water. In Fig. 1 the gases are discharged upwardly through a suitable injector nozzle 21 so that these gases act to lighten and raise 80 the water on the principle of the air-lift pump, while the gases also act because of their high pressure and velocity, as in an injector. In Fig. 1 the flow of water is indicated by the arrows and the discharged gases 85 are also illustrated, but it will be understood that such illustration is intended to be merely diagrammatic and that the relative amount of gas discharged can be varied within rather wide limits. With pump conduits into which the gases are discharged against a high head of water the gases will remain in a highly compressed state near the bottom of the conduit but will expand as they rise and as the pressure decreases. The 90 admission of the compressed gases should be below the normal water level of the water to be pumped so that this water will flow in without suction, although the invention is also applicable where suction means are provided for priming the pump and supplying the water thereto. In Figs. 1 and 2 a by-pass 95 22 is shown leading from the inlet 17 to the casing 6 below the valve, this by-pass being provided with a cut-off valve 23 and check 100 valve 24, and the outlet 25 of said by-pass being arranged to be acted upon by the escaping gases so that water can be drawn in to cool the valve, such water being vaporized and the resulting steam cooling the 105 valve and escaping with the gases.

In the embodiment of the invention illustrated in Figs. 4 to 6, a similar arrangement of engine and pump conduit is illustrated, but the valve 9 of Fig. 4 is positively operated instead of being operated as a pressure relief valve spring-pressed against the seat. This valve 9 of Fig. 4 is operated by a valve stem 10 adjustable with respect thereto and connected at its end to a rocker 120 arm 27 operated through a connecting rod 28 from a bell-crank lever 29 suitably actuated by a cam 32 carried by a cam sleeve 30 upon the cam shaft 31, which shaft is connected to the engine shaft by the usual two 125 130

to one gearing. The cam sleeve 32 is adjustable on its cam shaft so that the period of opening and closing of the valve 9 can be varied, operation of this sleeve being effected by the rod 33 and handle 34. The inlet and exhaust valve connections and operating rods are also shown in Figs. 4 to 6, the exhaust cam sleeve 35 acting upon a connecting rod 36 operating upon the exhaust valve 37 while an inlet cam sleeve 38 acts upon a connecting rod 39 operatively connected to the inlet valve, the casing of which is indicated at 40. The cylinder is surrounded with a water jacket 41 of any suitable construction.

In Fig. 7 the invention has been illustrated as applied to a pump conduit arranged to pump water from below ground, such as in a well. The engine is illustrated 20 diagrammatically and may be similar to that of Fig. 1. The high pressure gases are discharged through the conduit 45 past the check valve 46 and down through the central pipe 47 from the bottom of which they 25 escape, control of the operation being effected by the valve 48. The pipe 47 is shown as centrally arranged within the pump conduit 50 arranged within the well casing 51. The operation of the pump will 30 be clear from the diagrammatic illustration of Fig. 7. The water and gases rising in the conduit 50 are shown as being discharged through a lateral discharge connection attached to the conduit 50 by means 35 of the connection 49. In the modification of Fig. 8 the injector outlet 44 for the gases is arranged to discharge into the pipe 45 and to entrain air through the pipe 43, the casing 42 being the surrounding casing for 40 the air and gas injector. The highly compressed gas together with the air drawn in with it is forced past the check valve 46 and thence into the pump conduit.

In Fig. 9 a further modification of the invention is illustrated generally similar to that of Fig. 1, but with means arranged 45 for circulating cooling fluid from the pump conduit through the cylinder jacket. The inlet conduit 18 is shown as provided with a by-pass pipe 60 having therein a cut-off valve 63 and check valve 61, said by-pass pipe leading to the water jacket of the cylinder from which the water is withdrawn by the pipe 62 by the injector action of the escaping 50 gases acting upon the outlet of this pipe. A valve 64 is shown in the pump conduit to regulate the flow therethrough.

In Fig. 10 a supplemental air inlet 62^a is illustrated discharging into the injector outlet 21, the arrangement being such that air can be drawn in with the escaping gases and the air lift action of the pump thereby increased.

In Fig. 11 a further embodiment of the invention is illustrated, the pump conduit 17

having a positively operated cut-off valve 64 arranged to cut off said conduit from the conduit 16 and to cut off the inlet for the compressed gases alternately, operation of this valve being effected by a valve rod 70 65, bell crank 66, connecting rod 67, and bell crank 68 operated by the cam 69 carried by the same cam shaft that carries the cam 32 acting upon the valve 9. The arrangement is such that when the valve 9 is open 75 the inlet 17 will be cut off to permit upward discharge of the working gases in the pump conduit 16, while the valve 64 will open the inlet 17 when the valve 9 is closed. The closing of the gas inlet by the valve 64 also 80 prevents or minimizes the inflow of water into the casing 6. In Fig. 12 the usual exhaust port of the engine is shown as having a conduit 70 connected thereto for conducting the exhaust gases in heat interchang- 85 ing relation with the pump conduit 18 in order to impart heat to said conduit.

The operation of the pump and engine of the present invention will be clear from the above description and from the illustration. 90 The engine, if a four-cycle engine, will operate as a compressor and igniter for the explosive charge, and a portion of this charge after ignition will be discharged into the pump conduit, the amount of such discharge being regulated by the tension of the spring with the spring pressed valve of Fig. 1 or by the adjustment of the cam sleeve 30 and the corresponding variation in the opening and closing of the valve 9 in the 100 construction of Figs. 4 to 6. When the discharge is cut off the remaining gases will do work within the cylinder and cause it to perform its normal engine functions, the fly wheel having the usual steadyng effect 105 thereon. When it is desired to use the engine for doing external work other than pumping, the discharge into the pump conduit can be correspondingly reduced or even in some cases entirely cut off. When utilized primarily as a pump the function of the engine will be that of a compression and ignition cylinder which will be self-operating and which will require a minimum of supervision and regulation. With a two-cycle engine it will be understood that the charge 110 is usually introduced under pressure while with a four-cycle engine the charge will be drawn in by suction and compressed within the cylinder before ignition. In some pump 120 conduits the discharge may take place through an injector inlet or nozzle (e. g., as in the construction of Fig. 1) while in others the discharge may take place directly, against the water column (e. g., as in the 125 construction of Fig. 11).

By utilizing the main portion of the charge in pumping water by the air-lift method, the gases will be cooled during their contact with the water and the water corre- 130

spondingly heated. The circulation of part of the water through the cylinder jacket as illustrated in Fig. 9, results in a further heating of the water and an increase in the efficiency of the pump and engine as a heat engine. The heating action can be further increased by the utilization of the exhaust by bringing the same into heat interchanging relation with the pump conduit in such manner as illustrated diagrammatically in Fig. 12.

The process of operating the engine and of pumping water or other fluid will be clear from the above description, this process being so carried out that the desired discharge for pumping purposes is effected, while the necessary work is obtained within the cylinder for effecting the operation of the engine. It will be understood that this process can be varied within rather wide limits in accordance with the effect desired in the pump or in the engine or in both. When used for pumping water the pump may advantageously be placed below the level of the water so that the water will flow by gravity into the pump conduit. The engine may however be arranged above the inlet level and this inlet effected by suction or by other means; or again the gas can be discharged downwardly into the pump conduit as indicated diagrammatically in Fig. 7. With this arrangement of Fig. 7 there is a further heating of the water by the gases passing down the central pipe before such gases are discharged at the bottom of the conduit. The pump of the present invention can be used in pumping against either high or low heads. The height to which the water can be pumped is materially increased when the air-lift construction is used, owing to the lightening action of the gases rising with the water.

The indicator diagram of Fig. 3, is illustrative of the operation of the pump of the present invention. The shaded portion indicates the working stroke of the engine. It will be understood that this diagram is given for purposes of illustration, and that it will vary with different types of engines and different conditions of operation.

While I have illustrated and described certain specific embodiments of the invention, yet it will be understood that the invention is illustrated by, but is not limited to, such embodiments, and that variations and modifications can be made therein without departing from the spirit and scope of the invention, as set forth in the accompanying claims.

60 I claim:—

1. An internal combustion engine pump comprising an internal combustion engine operating upon a regular cycle and provided with the usual inlet and exhaust valves and fly wheel, a pump conduit, means for

discharging part of the working gases from said engine into said conduit early in the working stroke of said engine, and means for cutting off said discharge before the completion of the working stroke.

70

2. An internal combustion engine pump comprising an internal combustion engine operating upon a regular cycle and provided with the usual inlet and exhaust valves and fly wheel, a pump conduit, a duct connecting said engine with said conduit, and valve means controlling flow through said duct arranged to permit flow from said engine to said conduit early in the working stroke of said engine, and to cut off such flow before the end of the working stroke.

75

3. An internal combustion engine pump comprising a four-cycle internal combustion engine having valve-controlled inlet and outlet, a pump conduit, means for discharging part of the working gases from said engine into said conduit early in the working stroke of said engine, and means for cutting off said discharge before the completion of the working stroke.

80

4. An internal combustion engine pump comprising a pump conduit, an internal combustion engine operating upon a regular cycle and provided with the usual inlet and exhaust valves and fly wheel, and having an outlet through the cylinder head leading to said conduit, and valve means controlling said outlet arranged to permit flow from said engine to said conduit early in the working stroke of said engine, and to cut off such flow before the end of the working stroke.

85

5. An internal combustion engine pump comprising a pump conduit, an internal combustion engine operating upon a regular cycle and provided with the usual inlet and exhaust valves and fly wheel, and having an outlet from the engine cylinder to said conduit, valve means controlling said outlet arranged to permit flow from said cylinder to said conduit early in the working stroke of said engine and to cut off such flow before the end of the working stroke, and means for varying the period during which such valve remains open.

90

6. An internal combustion engine pump comprising an internal combustion engine operating upon a regular cycle and provided with the usual inlet and exhaust valves and fly wheel, a gas-lift pump conduit, means for discharging part of the working gases from said engine upwardly into said conduit early in the working stroke of said engine, and means for cutting off said discharge before the completion of the working stroke.

95

7. An internal combustion engine pump comprising an internal combustion engine operating upon a regular cycle and provided with the usual inlet and exhaust valves and

100

fly wheel; a gas-lift pump conduit of general U-shape, means for admitting liquid to one side of said conduit, a duct connecting said engine with the other side of said conduit and terminating in an injector nozzle in said conduit, and valve means controlling flow through said duct arranged to permit flow from said engine to said conduit early in the working stroke of said engine, and 10 to cut off such flow before the end of the working stroke.

8. An internal combustion engine pump comprising a pump conduit, a four-cycle internal combustion engine having valve-controlled inlet and outlet, and having a separate outlet from the engine cylinder to said conduit, and valve means controlling said outlet arranged to permit flow from said cylinder to said conduit early in the 20 working stroke of said engine and to cut off such flow before the end of the working stroke.

9. An internal combustion engine pump comprising a pump conduit, a four-cycle internal combustion engine having valve-controlled inlet and outlet, and having a separate outlet from the engine cylinder to said conduit, valve means controlling said outlet arranged to permit flow from said cylinder 30 to said conduit early in the working stroke of said engine and to cut off such flow before the end of the working stroke, and means for varying the period during which such valve remains open.

35 10. An internal combustion engine pump comprising a pump conduit, an internal combustion engine operating upon a regular cycle and provided with the usual inlet and exhaust valves and fly wheel, and having 40 an outlet through the cylinder head leading to said conduit, and an outwardly opening spring-pressed valve controlling said outlet arranged to permit flow from said engine to said conduit early in the working stroke of 45 said engine, and to cut off such flow before the end of the working stroke.

11. An internal combustion engine pump comprising a pump conduit, a four-cycle internal combustion engine having valve-controlled inlet and outlet, and having a separate outlet from the engine cylinder to said conduit, and an outwardly opening spring-pressed valve controlling said outlet arranged to permit flow from said cylinder to 50 said conduit early in the working stroke of said engine and to cut off such flow before the end of the working stroke.

55 12. An internal combustion engine pump

comprising a pump conduit, a four-cycle internal combustion engine having valve-controlled inlet and outlet, and having a separate outlet from the engine cylinder to said conduit, and an outwardly opening spring-pressed valve controlling said outlet arranged to permit flow from said cylinder to 60 said conduit early in the working stroke of said engine and to cut off such flow before the end of the working stroke, and means for varying the period during which such valve remains open.

70 13. The process of converting heat energy into power and of pumping liquids and fluids with the energy thus converted which comprises igniting an explosive charge in the cylinder of an internal combustion engine, discharging part of the resulting gases from said cylinder early in the working stroke of said engine into a pump conduit to pump the liquid or fluid therein, cutting off such discharge before the end of the 75 working stroke and expanding the remaining gases in said cylinder to operate the engine.

80 14. The process of converting heat energy into power and of pumping liquids and fluids with the energy thus converted which comprises igniting an explosive charge in the cylinder of an internal combustion engine, injecting part of the resulting gases from said cylinder early in the working 85 stroke of said engine into a pump conduit through a suitable injector inlet to pump the liquid or fluid therein, cutting off such discharge before the end of the working stroke and expanding the remaining gases in said 90 cylinder to operate the engine.

95 15. The process of converting heat energy into power and of pumping liquids and fluids with the energy thus converted which comprises igniting an explosive charge in 100 the cylinder of an internal combustion engine, discharging part of the resulting gases from said cylinder early in the working stroke of said engine into a pump conduit below the liquid level therein to elevate and 105 pump the liquid, cutting off such discharge before the end of the working stroke and expanding the remaining gases in said cylinder to operate the engine.

110 In testimony whereof I affix my signature in the presence of two witnesses.
